POINT-DETONATING FUSE FOR
PROJECTILES

David L. Woodberry, Edgewood Arsenal, Md.

Application February 7, 1934, Serial No. 710,064

7 Claims. (Cl. 102—39)

(Granted under the act of March 3, 1883, as
amended April 30, 1928; 370 O. G. 757)

The invention described herein may be manufactured and used by or for the Government for governmental purposes, without the payment to me of any royalty thereon.

The invention described herein relates in general to a combination of actuating mechanisms that when assembled as hereinafter described makes a point-detonating fuse.

An object of this invention is to provide a point-detonating fuse for projectiles used with rifled bore pieces where the projectile is rotated and gives true flight and impacts nose first.

Another object of this invention is to provide a point-detonating fuse for projectiles used with smooth bore pieces where the projectile does not necessarily rotate but gives true flight and impacts nose first.

Another object of this invention is to provide a point-detonating fuse having the detonator out of alignment with the firing pin and the bursting charge until the projectile to which the fuse is assembled is ejected from the muzzle of the piece and set-back force ceases to a degree where the spring under the firing pin will cause the firing pin to move forward releasing the detonator carrier, which then due to centrifugal force, and, or spring action, slides over and aligns the detonator with the firing pin and the bursting charge.

A further object of this invention is to provide a point-detonating fuse having a firing pin safely locked against movement prior to being ejected from the piece.

A still further object of this invention is to provide a point-detonating fuse having a firing pin safely locked against movement until ejected from the piece and set-back force ceases.

Another object of this invention is to provide a point-detonating fuse having a base which may be varied in dimensions to fit into the nose of a shell with varying openings.

Still another object of this invention is to provide a fuse that will not function or cause the projectile to burst in the event that ranges under 300 yards are obtained with the projectile.

With these and other objects in view which may be incident to my improvements, this invention consists in parts and combinations to be hereinafter set forth and claimed with the understanding that the necessary elements comprising my invention may be varied in construction, proportions and arrangement, without departing from the spirit and scope of the appended claims.

In order to make my invention more clearly understood, I have shown in accompanying

drawings means for carrying the same into practical effect without limiting the improvements in their useful applications to the particular constructions, which for the purpose of explanation, have been made the subject of illustration. In 5 the drawings forming a part of this specification:

Figure 1 is a longitudinal sectional view of the fuse fully loaded and assembled ready to be further assembled into the nose of a projectile. 10

Figure 2 is sectional view of the fuse taken on line 2—2 of Figure 1, showing the position of the shear-wire before being fired from the piece.

Figure 3 is a sectional view of the fuse taken on line 3—3, of Figure 1, showing the position of 15 the detonator carrier, detonator, lock pin, and guide pin, before firing from the piece.

Figure 4 is a longitudinal part sectional view showing the position of the firing pin, safety pin, and firing pin stop, before firing from the piece. 20

Figure 5 is a longitudinal sectional view of the fuse assembled to a projectile being ejected from the piece showing the retaining ring in the set-back position freeing the two steel balls.

Figure 6 is a longitudinal sectional view of the 25 fuse and the projectile in flight showing the retainer ring in the set-back position, the balls out into the groove of the retaining ring, the firing pin in the forward position, the detonator carrier in the armed and locked position aligning the detonator with the firing pin and bursting charge. 30

Figure 7 is a sectional view of the fuse taken on line 1—1 of Figure 6 showing the detonator carrier in the armed and locked position, while in flight. 35

Figure 8 is a longitudinal sectional view of the fuse on impact showing the firing pin driven into the detonator which initiates the functioning of the bursting charge.

Figure 9 is a sectional view similar to Figure 1 40 of a slightly modified form of fuse for use with projectiles fired from smooth bore guns.

Figure 10 is a section similar to Figure 9 of a modified form.

Referring more particularly by numerals to the 45 drawings in which the same and similar elements are designated by like symbols of reference throughout, and more particularly to Figure 1, the fuse body 1 is formed at the top with a truncated head portion 2 and at the bottom with a 50 downward projecting neck 3. The head portion 2 is provided with a horizontal bore 4 and a vertical bore 5 of smaller varying diameters. The bore 4 is closed at one end and opens into one face of the fuse head at the other, while the bore 5 55

opens into the nose at one end and communicates with the bore 4 at the other.

The neck 3 is provided with a vertical bore 6 opening in the bottom thereof at one end and 5 communicating at the other with the smaller bore 7 opening into the horizontal bore 4, the same corresponding with and being in alignment with the vertical bore 5 opening into the other side thereof. The horizontal bore 4 in the head is 10 extended to the outer portion of the fuse by a constricted bore. The nose of the fuse body 1 is provided with a centrally located annular groove 9. A firing pin 10 having an integral point 11 is adapted to be fitted into the vertical bore 5. The 15 outer end of the firing pin is provided with a disk head 12, formed as an integral part thereof or as a separate part suitably fixed thereto. Disk head 12 normally rests against the forward end of the fuse body 1, and is held in this position before firing 20 by two steel balls 13 and 14, the balls being held in position by a retainer sleeve 15. Sleeve 15 is slidably received in annular groove 9 of fuse body 1 and held in advanced position by a shear wire 16 and safety pin 17 extending therethrough 25 and through corresponding openings in fuse body 1.

Steel balls 13 and 14 seat into annular grooves on opposite sides of firing pin 10 and with the sleeve 15 in the upper position shown in Figure 1 30 these balls may not move outwardly, thus locking firing pin 10 in lowered position. By removing safety pin 17 and by shearing wire 16, retaining sleeve 15 is free to move downwardly into groove 9 so as to free balls 13 and 14, thus freeing firing 35 pin 10.

Shear wire 16 is adapted to be sheared off upon "set-back", that is, by the very rapid forward movement of the shell when fired, causing the sleeve 15 to move downward in its groove 9. 40 In order to protect personnel firing shells having this fuse mechanism, and those in an advanced position over whose heads the shells are to be fired, the shear wire 16 is so designed that it will not shear off when the "set-back" force is 45 less than a predetermined amount. Thus the wire 16 and the weight of sleeve 15 may be so designed that for ranges under 300 yards the "set-back" will be insufficient to shear wire 16, so that if for any reason the propellant charge 50 is defective or insufficient the shell will not arm and can not explode.

Firing pin 10 is urged forward, to armed position, by a spring 18 seated in socket 5, but pin 10 is locked in lowered position by balls 13 and 55 14. Positioned within the cross bore 4 is a detonator carrier 20 having a vertical aperture extending therethrough near one end for carrying a detonator charge 21. Carrier 20 has a vertical aperture 22 extending about half-way through 60 the central portion thereof, this opening 22 and the opening for detonator charge 21 communicating at their upper ends with a longitudinal slot 23 in carrier 20. Slot 23 decreases in depth toward its right hand end as seen in Figure 1, 65 and is narrower than firing pin 10, the aperture 22 and opening for charge 21 continuing through slot 23 as grooves (see Figure 6). Aperture 22 is adapted to receive the lower end of firing pin 10 to lock detonator carrier 20 in safe position 70 as long as the firing pin is locked by balls 13 and 14 and sleeve 15. After insertion of carrier 20, the cross bore 4 is closed by screw cap 24.

Cross bore 4 is constricted at one end to provide a shoulder 25 for engagement by a corresponding shoulder 26 on carrier 20, to limit out-

ward movement of the carrier. Referring to Figures 3 and 7, carrier 20 has an aperture 27 in which is seated a movable pin 28 slightly shorter than the aperture. The shell body has an aperture 29 into which pin 28 moves after carrier 20 5 has moved to firing position.

Opposite aperture 29, carrier 20 is provided with a longitudinal slot 30 into which projects the inner end of guide pin 31. Pin 31 is threaded into shell body 1 in alignment with aperture 10 29, to facilitate machining. Guide pin 31 allows free reciprocation of carrier 20 but prevents rotation thereof, thereby maintaining pin 28 in alignment with opening 29 and charge 21 in alignment with firing pin 10. 15

Accidental shearing of wire 16 during shipping and handling of the shell is prevented by the removable pin 17 which passes through sleeve 15, fuse body 1, and firing pin 10. Thus prior to removal of safety pin 17 the firing pin 10 is 20 locked down by balls 13 and 14 and pin 17, thus locking charge carrier 20 in the safe position by engagement of the lower end of firing pin 10 in aperture 22 of carrier 20. Removal of safety pin 17 prior to firing is facilitated by pull ring 32 25 secured thereto.

The restricted vertical bore 1, Figure 1, communicating with cross bore 4 contains an explosive train 33 in contact with a bursting charge within a tube 34, the tube 34 being screw-threaded 30 into bore 6 of base 3 of shell body 1.

As seen in Figure 4, the head 2 of fuse 1 has a screw threaded aperture communicating with bore 5 in which is threaded a bolt 36 having its inner end 37 fitting into a longitudinal groove 38 35 in firing pin 10 to limit outward movement of the firing pin. Sleeve 15 has a slot 39 for receiving the head of bolt 36, thus preventing rotation of sleeve 15 thus facilitating assembly since the opening in this sleeve must align with those in 40 shell body 1 to receive shear pin 16 and safety pin 17.

After the fuse has been assembled the neck 3 is screwed into a shell 41 (Figure 5). Shell 41 is adapted to be fired from a rifled barrel, since 45 the safety devices are released by rotation of the shell in flight. The invention is illustrated in connection with shell for a chemical mortar, i. e., wherein the shell has a propellant charge secured to its base and is dropped into the muzzle 50 of the mortar, but it may obviously be used with any rotating shell.

The operation of the invention is as follows. After assembly of the fuse the neck 3 is screwed into the end of the shell 41 (Figure 5), the parts 55 being in the position shown in Figure 1. Premature firing cannot occur due to the various safety features, the charge carrier 20 being held with the charge 21 out of alignment with explosive train 33 by engagement of the lower end of 60 firing pin 10 in opening 22; firing pin 10 is locked down in same position by steel balls 13 and 14 and by safety pin 17; balls 13 and 14 are locked by sleeve 15; and sleeve 15 is locked in upper safe position by pin 17 and shear wire 16. 65

When the shell is to be fired, safety pin 17 is withdrawn. However, the parts are still locked in safe position by shear wire 16. The shell is now fired, in the case of the mortar, by dropping the same in the open end of the barrel, and the rapid 70 forward acceleration causes the sleeve 15 to move backward in its slot, thus shearing off wire 16. As previously pointed out, if the range of the shell is less than a predetermined minimum, this "set-back" force will be insufficient to shear wire 16 75

and the shell will not explode as the parts remain locked in safe position.

The downward movement of sleeve 15 at once releases balls 13 and 14, thus freeing firing pin 10 for forward movement under force of spring 18. However, the "set-back" force on forward acceleration of the shell retains the firing pin locked until after the shell has left the gun barrel and acceleration decreases to a point where spring 16 moves pin 10 outward. The steel balls 13 and 14 move to the position shown in Figure 6 but are retained from dislodgment from the shell by shoulders 40 on sleeve 15. Thus the balance of weight of the shell is not changed by parts falling free therefrom in flight.

Until the firing pin 10 moves outward to the position shown in Figure 6, charge carrier 20 is locked in safe position, even though centrifugal force due to rotation of the shell tends to move carrier 20 outward. When released by movement of the firing pin, carrier 20 at once assumes the position of Figure 6, it being noted that a preponderance of weight of the carrier 20 is toward the right, Figure 6. The guide pin 31 in connection with slot 30 prevents rotation of carrier 20, and engagement of shoulders 25 and 26 limits outward movement thereof, thus accurately aligning charge 21 with end 11 of firing pin 10 as in Figure 6. In this position locking pin 28 is aligned with opening 29 and centrifugal force causes the pin to move to the position shown in Figure 7, thus locking carrier 20 in firing position. On impact of the shell, the firing pin 10 is driven into charge 21, as seen in Figure 8, the charge 21 in turn detonating explosive train 13 and exploding the shell.

In the event that the shell is to be fired from a smooth bore mortar or gun, where no centrifugal force is present to operate the carrier 20, a spring is used. As seen in Figure 9, a coiled spring 42 is interposed between nut 24 and the end of carrier 20. The lock pin 28 and aperture 29 are eliminated as unnecessary since the spring 42 will hold carrier 20 in firing position. The remaining parts are similar to the form shown in Figures 1 to 8 and this fuse acts in the same manner as regards release of the carrier 20 by "set-back". As soon as firing pin 10 moves outwardly the carrier is forced over by spring 42 to firing position.

Another modified form is shown in Figure 10 which is simpler to manufacture and assemble. Again the lock pin 28 and opening 29 are eliminated, this form, however, being adapted for shells fired from rifled gun barrels. The firing pin and release mechanism is the same as previously described. However, in the form shown in Figure 10 the guide pin 39 is eliminated and replaced by a combined guide and locking pin.

In this form, the fuse head 1 has a threaded opening communicating at its inner end by a constricted aperture with the guide slot 30 in charge carrier 20. Into this opening is screwed a cup member 43 housing a smaller cup member 44 having a pointed pin 45 projecting out of the constricted opening in member 43 and operating in slot 30 of carrier 20. A coiled spring 46 urges member 44 out of member 43, causing pin 45 to engage charge carrier 20.

An aperture 47 in the slot 30 of carrier 20 is so positioned that it aligns with pin 45 when carrier 20 is in firing position. The two cup members 43 and 44 are readily assembled as a unit prior to assembly with the fuse, the mouth of outer cup

member 43 being upset sufficiently to maintain the assembly.

The operation of this form is as follows. When the firing pin moves upward, thus releasing carrier 20, centrifugal force moves the carrier to firing position, the end of pin 45 preventing rotation of carrier 20 by way of slot 30. It will be noted that centrifugal force also tends to throw inner cup member 44 outward but the clearance between the inner end of this cup is insufficient to allow pin 45 to move out of slot 30. The effect of centrifugal force on cup 44, therefore, is to relieve the friction between pin 45 and carrier 20, thus allowing the carrier to move more easily. When the shell reaches the point in its trajectory at which centrifugal force is no longer sufficient to overcome spring 46, the cup 44 moves inward and pin 45 enters aperture 47, thus locking carrier 20 in firing position. This locking occurs before impact of the shell.

The form shown in Figure 10 may be readily converted for use with unrifled barrels by merely placing a spring similar to spring 42, Figure 9, in back of carrier 20. This spring will not interfere in any way with the mechanism of the fuse whether the shell is to be used with rifled or unrifled barrels, so that if a consignment of shells for mortars is to be used partly with rifled barrels and partly with unrifled barrels, the springs may be placed in all fuses and the shells may be used in either type of barrel.

This same advantage of use with rifled or unrifled barrels is true also of the form shown in Figure 9, save and to some extent by

There is accomplished by this invention a point-detonating fuse for use with either a smooth bore or rifled barrel having a detonator carrier locked in position with the detonator charge out of alignment with the striker pin and the explosive train, the detonator charge adapted to be aligned and locked in firing position after the shell leaves the gun barrel. The firing pin is triple locked against movement in handling and storage, double locked during insertion into the barrel of the gun, single locked on firing, and armed in flight. Explosion of the shell is prevented for ranges below a predetermined minimum. Furthermore, the fuse is readily convertible for use with rifled or smooth bore guns, and, with the spring back of the charge carrier, may be used with either type of barrel. With the "set-back" operated element and other movable parts in the nose and mid-section of the fuse body, the base of the fuse may be varied in diameter to fit projectiles with a small or large opening therein for receiving the fuse mechanism.

While I have shown and described the preferred embodiments of my invention, I wish it to be understood that I do not confine myself to the precise details of construction herein set forth by way of illustration, as it is apparent that many changes and variations may be made by those skilled in the art without departing from the spirit of the invention nor exceeding the scope of the appended claims.

I claim:

1. An impact fuse for projectiles comprising a fuse body, a bursting charge mounted thereon, a longitudinally movable firing pin in alignment with said bursting charge, a transversely movable member interposed between said firing pin and bursting charge, a detonator charge carried by said member, a shear member locking said firing pin into engagement with the transversely movable member and holding the detonator charge

- out of alignment with the firing pin, means operable by initial acceleration of the shell when fired to break said shear member and release said firing pin, and means operable upon a predetermined decrease in acceleration to move said firing pin to release said transversely movable member.
5. An impact fuse for rotating shells comprising a fuse body, a bursting charge carried thereby, a transversely movable member, a detonator charge on said member, a longitudinally movable firing pin, means including a shear element normally holding said firing pin in interlocked engagement with said transversely movable member, said means being released upon initial acceleration of the shell when fired, and means for moving said transversely movable member to armed position with the detonator charge aligned with the firing pin during flight of the shell, all parts of the fuse and safety mechanism remaining attached to the fuse during flight whereby the balance of weight is maintained and accuracy of fire is increased.
10. An impact fuse for shells comprising a fuse body having a base adapted for attachment to a shell, a bursting charge on said fuse body, a longitudinally slidible firing pin, a transversely movable member carrying a detonator charge, safety mechanism including a shear element for holding said firing pin and transversely movable member in unarmed position, and means for arming said fuse in flight, all movable parts of said fuse being positioned in the nose of the fuse whereby the base of the fuse may be adjusted to varying sizes of shell.
15. An impact fuse for shells comprising a fuse body, a bursting charge carried thereby, a transversely movable member carrying a detonator charge, a longitudinally movable firing pin adapted to interlock with the transversely movable member to hold the same in safe position, a spring tending to move said firing pin to armed position,

detent means holding said firing pin interlocked with said member, means to release said detent means by initial acceleration of the shell when fired, and means to limit transverse movement of said member when released by the firing pin to cause alignment of the detonator charge and firing pin, the end of the transverse member being out of contact with the barrel of the gun.

5. An impact fuse for projectiles comprising a fuse body, a bursting charge carried thereby, a transversely slidible member carrying a detonator charge, a longitudinally movable firing pin adapted to engage the slidible member and lock the same in safe position, a spring biasing said firing pin forwardly to release said transversely slidible member, detent means retaining said firing pin in safe position, a longitudinally slidible sleeve locking said detent means in engagement with said firing pin, and a shear member retaining said sleeve in position and breakable upon initial linear acceleration of the projectile.

6. The invention as described in claim 5 wherein the detent means comprises a plurality of balls, said longitudinally slidible sleeve allowing release of said balls but retaining them on the fuse body.

7. An impact fuse for projectiles comprising a fuse body, a bursting charge carried thereby, a longitudinally slidible firing pin, a transversely slidible member interposed between said firing pin and bursting charge and carrying a detonator charge, latch means retaining said firing pin interlocked with said slidible member, a shear wire retaining said latch means in position and sheared by initial linear acceleration of the projectile, and a spring biasing said firing pin out of engagement with said slidible member to armed position, said spring moving the firing pin only after a predetermined decrease in linear acceleration of the projectile.

40

DAVID L. WOODBERRY.
